UNITED STATES PATENT OFFICE.

WILLIAM E. CLAYTON, OF ALTOONA, KANSAS.

SUPPORTING DEVICE.

1,218,055.

Specification of Letters Patent. Patented Mar. 6, 1917.

Application filed March 23, 1916. Serial No. 86,263.

To all whom it may concern:

Be it known that I, WILLIAM E. CLAYTON, a citizen of the United States, residing at Altoona, in the county of Wilson and State 5 of Kansas, have invented new and useful Improvements in Supporting Devices, of which the following is a specification.

This invention relates to a supporting device designed particularly for use as a fixture in connection with zinc furnaces for the purpose of holding the zinc condenser in proper position relative to the zinc retort.

Supporting devices of this character are commonly known as "grass-hoppers," and 15 are employed for the purpose of holding the condenser in the proper position to receive the zinc from the retort and to prevent the condensed zinc from running back against the charge and either leaking at the butt or 20 becoming too hot and vaporizing and discharging through the condenser and becoming lost. Supporting devices or grass-hoppers of the character heretofore employed have been efficient only to a certain degree 25 for these purposes, but have not embodied the necessary adjustments to enable the condenser to be readily and conveniently adjusted to a predetermined position for proper working coöperation with the retort.

30 The object of my invention is to provide a supporting device or grass-hopper which, while simple of construction, is adapted to be adjusted to dispose the condenser in a proper position in a ready and convenient 35 manner.

A further object of the invention is to provide a supporting device or grass-hopper which may be manufactured and installed at a comparatively low cost.

40 The invention consists of the features of construction, combination and arrangement of parts hereinafter fully described and claimed, reference being had to the accompanying drawing in which:—

45 Figure 1 is a view in side elevation showing the bracket member in connection with the supporting rod.

Fig. 2 is a sectional elevation showing the bracket member in tilted position and ready 50 to be raised or lowered for adjustment.

Fig. 3 is a perspective view of the bracket member.

Referring to the drawing, 1 designates a 55 relatively stationary supporting member in the form of a rod having an enlarged portion provided with a series of annular grooves 2,

providing a plurality of intervening locking shoulders or surfaces 3. This rod is provided with transverse openings at its top and bottom to receive retaining pins 4, 60 whereby it is held from displacement when in applied position.

Provided for coöperation with the supporting rod or stationary bracket member is a relatively movable or adjustable bracket 65 member comprising a bracket bar 5 having a widened or enlarged portion or head 6 at one end thereof. This head 6 is provided with an upper guiding and retaining arm 7 provided with an opening 8 and a lower bifurcated or forked locking arm 9 of somewhat less length than the arm 7. The opening 8 adapts the arm 7 to be slidably and tiltably mounted upon the rod 1, so that the bracket bar may not only be raised and 75 lowered on said rod but may be pivotally tilted to throw the locking arm 9 into and out of engagement with the locking grooves and shoulders.

It will be understood by reference to Fig. 80 1 that the bar 5 is adapted to tilt downward under its own weight and any weight thereon, thus drawing the forward wall of the slot 7 in abutting contact with the rod 1 and forcing the bifurcated or forked arm 9 into 85 locking engagement with one or the other of the grooves 2, but that by tilting the arm outward and upward the fork 9 may be withdrawn from engagement with the rod and the bracket bar adjusted upwardly and 90 downwardly on the bar, the arm 7 sliding in contact with said bar, as will be readily understood, and that by this means of adjustment the fork 9 may be interlocked with any of the grooves 2 to dispose the bar 5 at 95 a greater or less elevation. Hence the device may be used to support and adjust the condenser as occasion may require to maintain it in proper position relative to the retort. It will be evident that the device is 100 simple in construction and may be made and sold at a comparatively low cost, and its convenience in operation for the purpose described will be readily appreciated.

105 I claim:—

A device of the character described comprising a vertically disposed rod having an enlarged portion provided with a series of annular grooves forming a plurality of intervening annular locking shoulders, and a supporting member comprising a bracket bar having a horizontal upper supporting 110

surface, said bar being enlarged vertically at one end to form a head provided with a pair of superposed arms at the upper and lower portions thereof, the upper arm being 5 provided with an opening to receive and engage the rod, said opening being of greater diameter than the rod to permit the bracket bar to have pivotal motion in a vertical plane, and the lower arm being relatively 10 shorter than the upper arm and bifurcated

to form a fork to partially embrace the rod and interlock with any of said annular grooves between adjacent shoulders.

In testimony whereof I affix my signature in presence of two witnesses.

WILLIAM E. CLAYTON.
